DESIGN FOR AN AX HEAD

Howard A. Vaughan, Evanston, Ill., assignor to Vaughan & Bushnell Mfg. Co., Chicago, Ill., a corporation of Illinois

Application March 16, 1935, Serial No. 55,896

Term of patent 7 years

To all whom it may concern:

Be it known that I, Howard A. Vaughan, a citizen of the United States, residing at Evanston, in the county of Cook and State of Illinois, have invented a new, original, and ornamental Design for Ax Heads, of which the following is a specification, reference being had to the accompanying drawing forming a part thereof.

Fig. 1 of the drawing is a side view of an ax head embodying my new design; and

Figs. 2 and 3 are rear and end views respectively.

The present ax head embodies as the dominant and essential feature a pair of wings which are coextensive and formed integrally with the inner end portions of the sides of the eye, are substantially equal in width from one end thereof to the other, and have rounded corners at the outer end portions thereof.

I claim:

The ornamental design for an ax head, substantially as shown and described.

Signed at Chicago, Illinois, this 13 day of March, 1935.

HOWARD A. VAUGHAN.
